FIG. I

FIG. II

FIG. III

FIG. IV

FIG. V

UNITED STATES PATENT OFFICE.

WILLIAM H. BOUTELLE, OF STURBRIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

EYEGLASS GUARD.

Application filed March 27, 1922. Serial No. 547,180.

To all whom it may concern:

Be it known that I, WILLIAM H. BOUTELLE, a citizen of the United States, residing at Sturbridge, in the county of Worcester, and State of Massachusetts, have invented certain new and useful Improvements in Eyeglass Guards, of which the following is a specification.

This invention relates to improvements in 10 eyeglass guards, and has particular reference to that type of guard comprising a metal backing and a composition covering for the face of the guard.

The principal object of the present invention 15 is the provision of a novel and improved manner of connecting the metal and non-metallic portions of the guard, which will eliminate objectionable projecting rivets or other metallic members coming in 20 contact with the face, as has been customary in the past.

A further object of the present invention 25 is the provision of an improved simplified construction which will render the manufacture of the guard much less expensive, in that it is possible to eliminate both the drawing over of the edges of the metal pad, or backing member, in the case of filled materials, and also in which the handling of 30 small rivet members, or the like, is entirely dispensed with.

A further object of the invention is the provision of a novel and improved construction of guard member which will have a 35 semi-suctional holding action on the face and therefore most firmly retain the mounting in position.

Other objects and advantages of my improved construction should be readily apparent by reference to the following specification taken in connection with the accompanying drawings, and it will be understood that I may make any modifications in the specific details of construction shown and 45 described within the scope of the appended claims without departing from or exceeding the spirit of my invention.

Figure I is a front view of a mounting embodying my improvements.

Figure II is a face view of a guard in which the pad portion is constructed in accordance with my invention.

Figure III is an enlarged rear view of the pad member.

Figure IV is a similar view of the metal 55 portion thereof.

Figure V is a sectional view as on the line V—V of Figure III.

Figure VI is a similar sectional view of 60 a different form of plate member.

Figure VII is a view of the drawn up composition member for application thereto.

Figure VIII is a sectional view through the completed pad or guard.

Figure IX is a face view of a different 65 shape of guard embodying my improvements.

Figure X is a perspective view of one form of rod stock from which the pad may 70 be produced.

Figure XI is a similar view of another form.

Figure XII is a plan view of a pad blank produced from Figure X.

Figure XIII is a sectional view as on the 75 line XIII—XIII of Figure XII.

Figure XIV is a view of a further step in the process of manufacture.

Figure XV is a plan view of the structure shown in figure XIV.

Figure XVI is a view of the completed pad.

In the drawings, the numeral 1 designates the bridge of an ophthalmic mounting supporting at each end the lenses 2 and having 85 the guard members 3 for retaining the mounting in position on the face. The invention here in question may relate either to the guard as an entirety or to the upper or what is commonly termed the pad portion 90 thereof, the invention being more particularly illustrated in connection with the pad portion of the guard as this is the most popular present day commercial form. The pad so termed comprises a metal backing 95 plate 4, having a rivet 5 normally loosely received in the upper portion of the arm 6 of the guard and a facing of zylonite, celluloid, or other composition material 7, which covers the front of the guard and 100 contacts with the face.

Prior to my invention it has been customary to secure this facing in position through the use of rivets, or the like, thus

producing metal members contacting with the face of the wearer, which has sometimes proved to be very undesirable on account of the chemical action caused by perspiration, or the like, on the end of the rivet. An additional disadvantage has been that the rivet apertures, no matter how well made, the mounting will in time form seats in which a verdigris deposit will take place rendering the mounting at once unsanitary and disagreeable in appearance.

It is the purpose of my invention to obviate all these defects and this I accomplish by forming the facing material 7 in cup-like formation with portions 8 extending over the edges of the material and portions 9 preferably tapered which are bent down and tightly clinched against the rear face of the main metal back plate 4. In this manner the facing material retains itself in place by its own inherent gripping properties and at the same time covers the edge 10 of the metal backing plate. This is also a feature of importance, since in prior constructions this edge has been either partially or entirely exposed. The large majority of mountings of the character here referred to, it is to be understood, are made from what is termed gold-filled material, or material having a base metal core and a gold filling, and considerable care has had to be taken in the manufacture of mountings of this sort to properly draw the gold-filled material over the cut edges of the back plate as it is stamped out. Even in spite of this care, the coating is relatively thin on these edges and is liable to wear or break through, again forming a source of verdigris and the like.

With my invention, however, the edge may, if desired, be left entirely rough and unfinished, since being covered and concealed by the overturned edges of the composition member it is entirely protected. If desired the edge may be stamped with the teeth serrations, prongs, or the like, 11, which bite into the composition material and more firmly hold it in place and eliminate any liability of loosening of the parts when worn.

Figures VI, VII, and VIII illustrate another possibility to which my invention particularly lends itself. In this form the back plate 4 is provided with a forwardly turned peripheral edge or flange portion 12, while the composition covering 7 is cupped or shaped to provide a corresponding projection 13 with recess 14 at the back to receive the flange 12 projecting therebeyond in the portions 9 adapted to be clinched down on the back of the backing plate, as illustrated in Figure VIII. This construction provides the recess 15 which, as the guard is applied to the face, will form a semi-vacuum chamber or space, the edges at 13 firmly en-

gaging the flesh, which will work up a certain amount into the pocket 15 and prevent slipping, yet holding without discomfort, biting edges, or the like, as has frequently been necessary in the past in order to properly retain a mounting.

Figure IX illustrates a face view of a complete or full length guard covered in accordance with my improvement, a cross sectional view of this being similar to the section shown in Figure V, for example.

It is to be understood that the zylonite covering member may be formed either from sheet material or from rod stock, such as shown in Figure X, or somewhat oval stock as shown in Figure XI, with one side slightly flattened as at 16. In either event the rod stock is cut off into discs which are then milled out as at 17 to provide an undercut recess to receive the metal back plate 4. The sides of the recess, as 8, are then opened out for insertion of the pad, and at the same time the material may if desired be stretched as from the round form of Figure XII to the ovalled form of Figure XV. In either event the material is then in condition for placing upon the pad 4, when the edges are turned back into their original or normal position as indicated in Figure XVI, when the material will grippingly retain itself by its own inherent set and resiliency.

I claim:

1. An eyeglass guard comprising a metal backing plate having projections and a composition covering for one face of the plate overlying said plate and being forced into interlocking engagement with the projections to retain it in position.

2. An eyeglass guard comprising a metal backing plate having projections and a composition covering for one face of the plate overlying said plate and being forced into interlocking engagement with the projections to retain it in position, said covering having portions overlying the lateral edges of the backing plate.

3. An eyeglass guard comprising a metal backing plate having projections and a composition covering for one face of the plate overlying said plate and being forced into interlocking engagement with the projections to retain it in position, said covering having portions overlying the lateral edges of the backing plate, and having additional portions crimped against the rear face of the plate.

4. An eyeglass guard comprising a back plate having a forwardly projecting flange providing a central recess and a non-metallic covering for that face of the plate shaped to correspond with the face configuration of the plate and overlying the flanged edges thereof.

5. The combination with a cupped metallic plate having an outstanding peripheral

flange, of a correspondingly cupped composition covering for one face of the plate fitted thereover and having inturned edge portions engaging the opposite face of the 5 plate for retaining it in position thereon.

6. The combination with a metallic backing plate having an outstanding peripheral rib, of a composition covering for one face there-
of shaped with an outstanding peripheral 10 rib providing a marginal channel receiving

the first rib, and having reversely bent terminal edge portions interlocking with the plate to retain it in position.

7. The combination with a composition covering provided with a marginal channel, 15 of a metallic backing plate having an outstanding peripheral rib to enter said channel.

WILLIAM H. BOUTELLE.
